UNITED STATES PATENT OFFICE.

EDWARD K. PATTEN, OF UTICA, NEW YORK.

JOINTING AND TRIMMING MACHINE.

SPECIFICATION forming part of Letters Patent No. 357,622, dated February 15, 1887.

Application filed May 29, 1885. Serial No. 166,995. (No model.)

To all whom it may concern:

Be it known that I, EDWARD K. PATTEN, of Utica, in the county of Oneida and State of New York, have invented certain new and useful Improvements in Jointing and Trimming Machines; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to that class of machines constructed for planing, trimming, jointing, and truing the sides, ends, edges, or angles of boxes, drawers, lumber, and other articles where a true edge is required; and it consists in a rotating head or heads carrying cutting-spurs and cutters mounted on independent shafts, in a feeding device for feeding the article to be operated on, and in other combinations and mechanical details hereinafter pointed out.

25 In the accompanying drawings similar letters of reference refer to corresponding parts throughout the several views.

Figure 1 is a section of the machine on line xx , Fig. 2. Fig. 2 is a plan view of the machine. Fig. 3 is a left-hand end view of the machine. Fig. 4 is a vertical section on line yy , Fig. 1. Fig. 5 is a side view of a feeding device and a section of the frame. Fig. 6 is a plan view of the same. Fig. 7 is an end view 35 of the feeding device and the section of the frame. Fig. 8 is a front view of the rotating head, showing the location and construction of the spurs and cutters in the face of the head. Fig. 9 is a section view of the head and a side 40 view of the pulley, the broken lines indicating a section of the upright. Fig. 10 is a view of the cutting-spur. Fig. 11 is a side view of a cutter. Fig. 12 is an end view of the cutting-spur and a section of the head, exposing 45 the retaining-bolt for securing the cutting-spur to the head. Fig. 13 is a side view of the retaining-bolt, and Fig. 14 is a top view of the same.

Having described my invention by reference 50 to the figures represented in the accompanying drawings, I will now proceed to describe

the same by reference to the letters marked thereon.

The machine represented in the drawings is constructed for truing, trimming, and smoothing opposite ends or sides of drawers, boxes, or other lumber. I do not, however, intend to limit myself to the use to which this machine may be applied, nor to the manner of constructing the same, as it is obvious that 55 the rotating head or heads, carrying suitable spurs and cutters, may be used in a variety of ways not illustrated for jointing, truing, and planing sides or angles of lumber where a plane or true edge is required, and may be accomplished by a single or by double heads, as 60 the case may require.

For trimming, planing, matching, smoothing, and truing the opposite surfaces of articles, I provide two heads mounted, preferably, on independent shafts journaled in stationary or movable uprights for supporting and carrying the rotating head. In the drawings the heads are mounted to be rotated vertically, and are driven by belts running on 65 suitable pulleys driven from the main line of shafting.

The working parts of the machine are shown mounted on frame A consisting of four legs united by suitable cross-ties, as shown, but 70 which may be of any other suitable and convenient construction.

B and B' represent heads in which are secured spurs.

b b b b represent four spurs or cutters, the 75 spur ends forming a cutting-surface and extending beyond the periphery of the head for forming a cutting-surface in line with the face of the spurs. These spurs are let into the face of the head by dovetailed grooves b' b' b' b'. 80 One or more of these spurs may be used. The spurs are fitted into the grooves and held by bolts b². The projecting ends of the spurs 85 should be brought to a sharp cutting-edge.

b' represents cutters set in the face of the 95 rotating heads, substantially in line with the spurs and extending beyond the periphery of the head to a point substantially in the same circle with the projecting ends of the spurs. These cutters are provided with cutting-edges, 100 as indicated in Fig. 11, and are set in the head substantially at right angles with the spurs

for cutting and cleaning the material cut and trimmed by the spurs. The cutters are held in grooves in the head by bolts substantially like that shown in Fig. 13. In the drawings 5 the heads are shown circular. While this form is preferable, those having angles may be used, the spurs and cutters being set in the projecting angles of the head. These heads provided with the spurs and cutters are mounted on 10 shafts a a and are held rigidly thereto by nuts or keys, or both, and are mounted in journals a' a' a' in the upper ends of uprights D D , and are driven by pulleys a^2 a^2 , rigidly held on the shafts by belts running on drum K , journaled 15 in the frame connected with driving-pulley P , which is connected with the main line of shafting, for imparting a rotating motion to the heads carrying the spurs and cutters.

To adjust the heads to different-sized articles to be operated on I provide movable uprights D D , which are mounted on rods e e , which pass through the uprights at e' e' e' e' , which slide on the rods, which are rigidly held at their extremities e^3 e^3 e^3 e^3 in the frame. In 20 the drawings the right-hand upright, D , is secured rigidly in position on the supporting rods by set-screws e^4 e^4 , the left-hand upright being movable to secure the proper adjustment by adjusting screw e^5 , one end working 25 in suitable bearings in the right-hand upright and the opposite end in the frame at e^6 , and is operated by hand-wheel e^7 for turning the screw-threads in the left-hand upright for horizontally moving the same to secure accurate 30 adjustment.

I disclaim the use and construction of a trimming-machine provided with four raised ways, with a movable carriage mounted thereon, two uprights in which are mounted to be 35 operated in parallel lines, two circular saws, with a right and left hand screw for moving the saws to or from a common center in the same right line, the said carriage moving between the saws for feeding the article to be 40 operated thereon.

For feeding the article to be operated on between heads carrying the spurs and cutters for simultaneously operating upon opposite angles, I provide tracks f f , with cross-grooves 45 f' f' , (shown in Fig. 5,) let into the same on the under side thereof. These grooves fit projecting flanges f^2 , Fig. 2, on the upper surface of the frame. In the drawings the right-hand track is held rigid by set screw f^3 . The 50 left-hand track is attached to the movable upright by braces f^4 f^4 and moves therewith. On the upper surface of the tracks are projecting flanges f^5 f^5 . It is obvious that either or both of these might be secured to the uprights, if so 55 desired. On the upper surfaces of these tracks are provided carriers G G , on the under side of which is a groove to fit the projecting flanges f^5 f^5 , for securing accurate movement. On the rear of each carrier is a projecting surface, g , 60 (shown in Fig. 5,) a similar one being provided on each, against which the article to be 65 operated

is driven by screws g g , working in bearings g^2 g^2 , operated by hand-wheel g^3 .

Operation: The operator sets the rotating heads to suit the article to be operated on. 70 The article is then placed on the carriers and crowded against projections g g , and rigidly clamped by turning the hand-wheels g^3 g^3 . The operator then crowds the article and carriers forward, which are moved in accurate line on 75 the flanges on the upper surface of the track until the article is passed between the rotating heads carrying the spurs and cutters. The carriage and article are then returned and the article removed from the machine. 80

What I claim as new, and desire to secure by Letters Patent of the United States, is—

1. In a machine for planing, trimming, jointing, and truing the sides, ends, edges, or angles of boxes, drawers, lumber, and other articles 85 where two edges are required to be parallel with each other, the combination of two heads mounted in two uprights and constructed to be rotated in the same direction in parallel planes, each head carrying one or more cutting spurs, and one or more clearing-cutters, arranged substantially as described, for the purposes stated. 90

2. In a machine for jointing and trimming the opposite angles or edges of boxes, drawers, 95 and other articles where parallel edges are required to be trued and for accommodating different widths of articles, the following mechanism in combination: two rotating heads, each carrying one or more spurs and one or more 100 clearing-cutters, arranged substantially as described, mounted in movable uprights, constructed and mounted to be adjusted in relation to each other substantially as described, for the purposes stated. 105

3. In a machine for jointing and truing opposite angles of articles varying in width in one operation, the combination of two rotating heads carrying spurs and cutters, as described, mounted in movable uprights, one or more of 110 which is adjustable horizontally, with means for adjusting the same, whereby the heads are moved to accommodate different sizes of articles to be operated on and to be held in fixed relation to each other, substantially as described, for the purposes stated. 115

4. In a machine for jointing and truing opposite angles or edges of articles varying in width in one operation, the combination of two rotating heads carrying spurs and cutters, 120 as described, mounted in movable uprights, each of which is adjustable horizontally and which may be held when adjusted in fixed relation to each other, whereby the rotating heads are moved to accommodate different 125 widths and sizes of articles to be operated on, substantially as described.

5. In a jointing and truing machine for truing opposite edges or angles in one operation, having two rotating heads carrying spurs 130 and cutters, the heads mounted in adjustable uprights, one of which is movable, as described,

the combination of two tracks fitted and moving on the frame and one of which is connected with the movable upright and adjustable therewith, and two carriers movable on the upper surface of the tracks and guided in relation thereto by flanges and grooves, substantially as described, whereby the article to be operated on is moved in parallel lines between the rotating heads, arranged substantially as described, for the purposes stated.

6. In a machine constructed for truing opposite angles of articles varying in width in one operation, substantially as described, the combination of two tracks fitted and moving on the upper portion of the frame on flanges fitting in grooves, one of said tracks held stationary, the

other attached to and adjustable with the upright carrying one of the rotating heads for adjusting the tracks, and two carriers movable on the upper surface of the tracks and guided in relation thereto by flanges and grooves, substantially as described, whereby the article to be operated on may be moved in parallel line between the rotating heads, substantially as described.

In witness whereof I have affixed my signature in presence of two witnesses.
